UNITED STATES PATENT OFFICE.

ADAM II. NIEDING, OF CLEVELAND, OHIO.

DESIGN FOR A CIGAR-BOX.

SPECIFICATION forming part of Design No. 28,729, dated May 31, 1898.

Application filed January 29, 1898. Serial No. 668,488. Term of patent 14 years.

To all whom it may concern:

Be it known that I, ADAM II. NIEDING, a citizen of the United States, residing at Cleveland, in the county of Cuyahoga and State of Ohio, have invented and produced a new and original Design for a Cigar-Box, of which the following is a specification, reference being had to the accompanying drawing, forming part thereof.

10 The figure is a perspective view of my newly-designed box.

As seen in the drawing, the leading feature of my design consists in the configuration of outline of the box. The sides and ends of the 15 box are formed with a wide groove A surrounding the entire body. The bottom pro-

jects a little and the edge is rounded to form a bead B around the base. The cover C also projects in like manner over the top. On the top surface of the cover is made a raised panel 20 D. The groove A shows an ornamental panel provided with the ornamentation shown.

Having described my invention, what I claim as new, and desire to secure by Letters Patent, is—

25 The design for a cigar-box, as herein shown and described.

ADAM II. NIEDING.
